M. HERSKOVITZ.
HANGER FOR LIGHT REFLECTING BOWLS.
APPLICATION FILED JUNE 30, 1915.

1,166,371.

Patented Dec. 28, 1915.

Recg. 3.

Inventor,
Max Herskovitz,
by Charles O. Shervey,
115 Attn.

UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF ILLINOIS.

HANGER FOR LIGHT-REFLECTING BOWLS.

1,166,371.

Specification of Letters Patent. Patented Dec. 28, 1915.

Application filed June 30, 1915. Serial No. 37,214.

To all whom it may concern:

Be it known that I, MAX HERSKOVITZ, a citizen of the United States, and a resident of Chicago, county of Cook, and State of Illinois, have invented certain new and useful Improvements in Hangers for Light-Reflecting Bowls, of which the following is declared to be a full, clear, and exact description.

10 This invention relates to hangers for light reflecting bowls, and its primary object is to provide a hanger of improved construction which may be readily attached to or detached from the light reflecting bowl without danger of cracking the same. Hangers which employ bolts that extend through holes in the light reflecting bowls are objectionable because the bowl is often cracked when screwing up the nuts on the bolts, and 20 the same objection is present in a hanger which employs a screw that bears against the inner side of the bowl for holding the hanger in place thereon.

The present invention is designed to obviate these objectionable features, and to provide a hanger with spring pressed securing means having the additional function of supporting the incandescent electric light socket, which usually accompanies hangers 30 for light reflecting bowls.

The invention consists in the several novel features fully described in the following specification and particularly defined in the claims.

35 The invention is clearly illustrated in the drawing accompanying this specification, in which:

Figure 1 is a side elevation of a hanger embodying a simple form of the present invention and showing the same applied to a light reflecting bowl, a fragment of which is shown in vertical cross section; Fig. 2 is a view partly in end elevation and partly in vertical cross section of the hanger shown 45 in Fig. 1, the line of section being indicated in 2-2 of Fig. 1; Fig. 3 is a detail cross section taken on the line 3-3 of Fig. 1; and Fig. 4 is a perspective view of the wire clamping member alone.

50 In the embodiment of the invention illustrated in said drawing, 10 designates a fragment of a light reflecting bowl having the usual outturned lip or rim, 11, upon its upper edge. The bowl is usually supported by 55 a plurality of hangers—usually three in

number, one of which is shown at 12, and said hanger comprises a supporting member, 13, having an upper hook, 14, to which is secured the suspending medium, usually in the form of a link chain, one of the links 60 of which is shown at 15. If desired, a lower hook, 16, may be provided upon the supporting member, 13, for supporting an incandescent electric light or other object outside of the bowl. Obviously various shapes 65 of supporting members may be employed, and they may be ornamented in any suitable manner.

The supporting member, 13, has a lip engaging portion, 17, which fits under and engages with the underside of the outstanding lip, 11, of the bowl, and to said lip engaging portion, 17, is secured a spring-like clamping member, 20, which is pivotally connected with said lip engaging member, 17, and has 70 a portion which engages with the inner side of the bowl to clamp the hanger and bowl together, said member, 20, also being arranged to support an incandescent electric 75 light socket, 18. In the form of clamping member shown in the drawings, a single piece of spring wire is employed, which is bent into the form of an eye at 21, at its middle portion, for supporting the socket, 18, and from which extend two arms, 22, that 80 are bent around, as at 23, to conform to the shape of the outstanding lip, 11, of the bowl, the terminal ends being bent around into eyes, 24, that are connected to and 85 pivoted upon the lip engaging portion, 17, of the supporting member, 13. Any form of connecting device between the member, 13, and clamping member 20, may be provided and a simple form is here shown as comprising outstanding lugs, 25, formed integral 90 with the lip engaging portion, 17, their ends being headed down upon the eyes, 24, of the spring clamping member, 20.

In securing a hanger embodying the present invention, to a light reflecting bowl, 100 the spring clamping member, 20, is swung back into the position shown in dotted lines in Fig. 1, the lip engaging portion, 17, of the member, 13, placed underneath the outstanding lip, 11, of the bowl, and thereafter the 105 clamping member, 20, swung down on the inside of the bowl, into the position shown in full lines in Fig. 1. In this position said clamping member engages with the inner 110 face of the bowl, and clamps the hanger to

the outstanding lip, said lip resting upon the lip engaging member, 17, and being securely held in place by the spring clamping member, 20. Furthermore, the weight of the electric light socket and incandescent lamp serves to hold said clamping member in engagement with the inner face of the light reflecting bowl; besides this, the spring-like arrangement of said clamping member acts 10 to clamp the supporting member and bowl together, so as to prevent accidental displacement. Furthermore, the wire clamping member, 20, may readily be bent by hand to fit the inner face of bowls, in case of slight 15 variations in contour.

More or less variation of the exact construction shown and described is possible, without departing from the spirit of this invention, and I desire, therefore, not to 20 limit myself to the exact form, but intend in the following claims, to point out all of the invention herein disclosed.

I claim as new and desire to secure by Letters Patent:

25 1. A hanger for light reflecting bowls, comprising a supporting member having a lip engaging portion adapted to engage with the underside of an outstanding lip of a light reflecting bowl, and a resilient 30 clamping member secured to the lip engaging portion of said supporting member and having a volute portion extending back over the lip of said bowl and engaging with the inner face of the light reflecting bowl underneath the lip engaging portion of the supporting member.

2. A hanger for light reflecting bowls, comprising a supporting member having a lip engaging portion adapted to engage with the underside of an outstanding lip of a light reflecting bowl, a resilient clamping member pivotally secured to said lip engaging portion and having a member extending over the top of said lip and down 45 and underneath the same to engage with the inner face of the bowl below the lip engaging portion of the supporting member, said portion being spring-pressed against the inner face of the bowl.

3. A hanger for light reflecting bowls, 50 comprising a bowl supporting member having a shoulder adapted to engage with the underside of an outstanding lip of a light reflecting bowl, and a resilient clamping member pivotally secured to the shoulder of 55 said bowl supporting member and having a volute portion engaging with the inner side of the bowl below said shoulder and spring-pressed toward said bowl supporting member.

4. A hanger for light reflecting bowls, comprising a bowl supporting member having a lip engaging portion adapted to engage with the underside of an outstanding lip 65 of a light reflecting bowl, a clamping member comprising a piece of wire bent at its middle to form an eye for supporting an incandescent electric light socket, and having two arms bent to conform to the inner face of the upper portion of the light reflecting bowl, its terminal ends being pivotally secured to the lip engaging portion 70 of the bowl supporting member one on either side thereof.

5. A hanger for light reflecting bowls, 75 comprising a hook-like bowl-supporting member having a shoulder portion for engaging with an outturned lip of a light reflecting bowl, and a resilient clamping member pivotally secured to said lip engaging 80 portion in front of the lip and having arms bent around behind said lip and arranged to bear against the inner side thereof and underneath said lip engaging portion, the inner end of said clamping member having 85 means for supporting an incandescent electric light socket.

6. A hanger for light reflecting bowls, comprising a supporting member having a lip engaging portion, a clamping member 90 pivotally secured to said supporting member in front of the lip and extending over and behind said lip to engage with the inner face of the bowl and terminating in a weighted arm acting to clamp the supporting member and bowl together.

MAX HERSKOVITZ.
